STRIPING BRUSH

Martin Panitzsch, Forest Park, Ill.

Application October 22, 1932, Serial No. 639,061

3 Claims. (Cl. 15—166)

The invention relates to a striping device for applying a stripe to a surface and particularly to walls, ceilings or other surfaces to decorate the latter.

5 The invention has among its principal objects the utilization of a striping element comprised of a block of cellular, absorbent and yieldable material capable of carrying and transferring paint or other material therefrom to an 10 article to be striped.

Another object of the invention is to mount a block of material such as that just referred to in a holder with a portion of said block extending from one end of the holder, the opposite end of 15 the holder being adapted to have a handle applied thereto to facilitate use of the device when employed by painters and decorators.

Another object of the invention is to employ a block of absorbent yieldable material as the 20 striping element and to mount the same in a tubular member in a manner so that it may be adjusted to allow one end of the block to protrude various distances from the end of the tubular member and thereby allow the length of the 25 protruding end of the block to be varied in accordance with the desires of the user.

Another object of the invention is to combine a tubular member and a striping element comprised of a block of material having the above 30 mentioned characteristics and to provide the tubular member with perforations to thereby allow the paint or other coloring medium to enter the tube and be applied to the striping block, and the end of the tubular member through which the 35 block projects being tapered and having a restricted portion which acts upon the block to adjustably hold the same with relation to the tubular member.

Another object of the invention is to provide 40 the block with means which facilitates its removal from the tubular element when cleansing thereof is desired.

In addition to the above, it is an object to employ a striping element of block form which is of 45 a material capable of being readily fashioned to conform with the configuration or cross sectional outline of a particular surface to be painted or colored.

The invention has these and other objects, 50 all of which will be explained in detail and more readily understood when read in conjunction with the accompanying drawing which illustrates one embodiment of which the invention is susceptible, it being manifest that changes and modifications may be resorted to without departing

from the spirit of the appended claims forming a part hereof.

In the drawing, Fig. 1 is a front elevation of a striping device constructed according to the invention;

Fig. 2 is a sectional view taken on line 2—2 of Fig. 1;

Fig. 3 is a sectional view taken on line 3—3 of Fig. 1;

Fig. 4 is a front elevation of the striping element employed in the structure shown in Figs. 1 and 2;

Fig. 5 is a side view of said element; and

Figs. 6 and 7 are front views of the striping element showing same constructed to apply a stripe to an object of irregular cross section.

The invention as herein illustrated and described is applied to a handle 10 having a ferrule or tubular element 11 combined therewith, the latter providing a mounting for the striping element 12. The striping element is formed of a block of cellular absorbent, yieldable and flexible material such as, for instance, a sponge of certain texture, felt or other fibrous material, the block being preferably formed to produce a side 75 and an end, either of which may be employed to apply a stripe.

One end of the tubular member 11 which in this instance provides a mounting for the striping element may be provided with an inwardly 85 projecting holding element 13 which is adapted to cooperate with the circumferential groove 14 provided in the handle 10 to hold these elements in separable associated relation with each other. The handle is also provided with the groove 15 90 to facilitate association and removal of the handle 10 and the tubular element 11.

The opposite end 16 of the tubular element 11 is preferably tapered and formed to provide a restricted opening 17 having the relatively flat 95 side walls 18—18. This end of the tubular member is provided with a plurality of perforations 19 to allow paint or other matter to enter the tube and be applied to the block or striping element 12 which acts as a carrier for the paint 100 and allows same to be transmitted therefrom to the surface of the article to be striped. The striping element 12 is arranged in the restricted portion 17 so that one end thereof such as 20 projects a suitable distance from the adjacent 105 end of the tubular element 11. It is understood that the striping block 12 is designed to be movably held in the restricted opening 17 so that the length of the protruding end 20 may be varied according to the desires of the user.

The striping element 12 may be provided with a cord 21 which will allow the striping element 12 to be extracted from the tubular element 5 should it be desired to replace the striping element or remove same for cleansing purposes.

As before stated, it is an object of the invention to employ a striping element which is composed of material which may be readily fashioned to conform with the particular cross sectional 10 outline of the article to be painted or striped, as indicated by the dotted line 23 in Fig. 4 or as indicated at 24 in Fig. 6 or in the manner indicated at 25 in Fig. 7, it being understood that these outlines are only employed to illustrate 15 a few of the many which may be resorted to.

From the foregoing description of the invention it is believed evident that the use of a block 20 of cellular, absorbent, flexible and resilient material produces a structure which provides a device capable of assisting a person of limited skill to 25 apply a stripe which is equal in appearance to one applied by a person particularly skilled in this branch of the painting and decorating art.

Having thus described the invention, what I 25 claim as new and desire to cover by Letters Patent is:

1. A striping device comprised of a tubular member having an end which is elongated in cross section and provides a restricted opening at 30 said end and a striping element mounted in said opening, said striping element being comprised of a block of cellular, absorbent, yieldable material, a portion of said block being extended in opposite directions beyond said restricted end of 35 said tubular member and to provide a portion

which extends into and is spaced from opposed walls of said tubular member and provides a flexible stripe applying portion, said block being movably held in said restricted opening of said tubular member to thereby vary the length of 80 the extending portion thereof.

2. A striping device comprised of a tubular member, one end of said tubular member providing means for receiving an end of an element 85 providing a handle, the opposite end of said tubular member being relatively narrow in cross section and being tapered from said end to the opposite end, said tapered end of said member having perforations provided therein, and a striping element comprised of a block of cellular, 90 absorbent, flexible material, said striping element being of a cross section substantially corresponding to the cross section of said end of said tubular member.

3. A striping device comprised of a tubular member and a striping element mounted in one end of said tubular member, said striping element being comprised of a block of cellular, absorbent, yieldable material, said tubular member being formed at said end in which said striping element 100 is mounted to provide means for engaging said striping element between the opposite ends thereof and provide a space between opposed sides of one end of said striping element and said tubular member, said end of said tubular member being 105 perforated to allow the introduction of paint to said space and the application thereof to said striping element.
